Primary Examiner — Jennifer Rivard*Assistant Examiner* — April Rivas(74) *Attorney, Agent, or Firm* — Dunlap Bennett & Ludwig PLLC(57) **CLAIM**

The ornamental design for a travel case, as shown and described.

DESCRIPTION

FIG. 1 is a perspective view of a travel case;

FIG. 2 is a front elevation view thereof;

FIG. 3 is a rear elevation view thereof;

FIG. 4 is a left elevation view thereof, the right elevation view being a mirror image thereof;

FIG. 5 is a top plan view thereof; and,

FIG. 6 is a bottom plan view thereof.

The broken lines illustrate environment and form no part of the claimed design.
